UNITED STATES PATENT OFFICE.

ENOS H. JOHNSON, OF LAGRANGE, ILLINOIS.

MEANS FOR TRANSMITTING POWER FROM CAR-AXLES.

SPECIFICATION forming part of Letters Patent No. 702,655, dated June 17, 1902.

Application filed March 27, 1901. Serial No. 53,027. (No model.)

To all whom it may concern:

Be it known that I, ENOS H. JOHNSON, of Lagrange, county of Cook, and State of Illinois, have invented certain new and useful 5 Improvements in Means for Transmitting Power from Car-Axes, of which the following is a specification.

This invention relates to means for transmitting power from car-axes, and is in the 10 nature of an improvement upon my previous invention patented January 16, 1894, and numbered 513,046.

The object of the present invention is to simplify in important respects the mechanical 15 construction and to carry out and embody in a practical and economical form a complete equipment for transmitting the power derived from the rotation of the car-axle to a machine, such as a dynamo, mounted in proximity thereto, the construction being such that the power-transmitting means and the power-using device—say a dynamo or fan—may all be mounted beneath the body of the car and in such manner as not to partake of 20 the oscillations of the car-body, being suspended on the truck and moving and turning therewith.

I have shown my invention as applied to a car-axle and connected for the driving of a 25 dynamo, the power-transmitting shaft being coupled to the dynamo-shaft by means of a friction-clutch.

In the drawings, Figure 1 is a plan view 30 showing the mechanism applied to the car-axle and the casing inclosing the driven dynamo. Fig. 2 is a side elevation of the same, the car-axle and a part of the truck-timbers showing in section and the car-wheel indicated by dotted lines. Fig. 3 is a plan section through the sleeve around the axle, some 35 of the gearing and the clutch mechanism being also in section. Fig. 4 is a vertical section through the gear-casing, taken at right angles to the car-axle, also shown in section. Fig. 5 is a side elevation of the gear-casing 40 and a part of the dynamo-casing, the former being in section to show particularly the parting of the gear-casing to enable it to be clamped around the axle. Fig. 6 is a longitudinal section of the gear-casing, showing a 45 power-transmitting counter-shaft, a driving-

gear, and clutch mechanism mounted thereon. Fig. 7 is a side elevation of one of the bevel-gears having a clutch member, and Fig. 8 is a perspective view of one shiftable 55 member of the clutch.

In carrying out the invention the purpose is to so mount the power-transmitting means as that it shall rock or oscillate around the axle, and in order to enable the application 60 to the axle without specially preparing the latter or detaching it from its truck I employ a counter-shaft, through which the power is transmitted, said counter-shaft being arranged parallel to the axle and contained 65 within a gear-casing, which is constructed to provide a lubricant-chamber, so that the gearing runs in the lubricant. The gear-casing is preferably connected to or provided at its forward end with a casing to contain the 70 driven or power-using device—say a dynamo. The gear-casing as well as the casing for the driven machine are so constructed that their parts may be separated to admit of quick application and detachment for the inspection 75 or repair of any of the working parts.

In the drawings, 10 represents the car-axle, the dotted line 11 the car-wheel, and 12 the truck-frame. In order to obviate the necessity of turning down or otherwise specially 80 treating the car-axle, I prefer to mount thereon a sleeve 13, Fig. 3, which may be constructed in sections, as shown at 14, Fig. 5, and secured to the axle by set-screws 15, which are held by the locking-screws 16. The sleeve 85 has cast thereon or secured thereto a gear 17 (see Fig. 3) and is preferably provided with circumferential grooves 18 to receive flanges of the gear-casing. The latter is made preferably in three sections 19 20 21, the upper 90 section 19 being bolted to the sections 20 and 21, and when the latter is removed the gear-casing, with its contained gearing, may be removed from or applied to the axle with all of its parts connected up, thus effecting not 95 only economy and readiness of application to car-axes already in service, but equal facility in removal for repairs or renewals. Within the gear-casing formed between the sections 19 20 is arranged a transmitting power-shaft 100 22, parallel to the axle and provided with a spur-gear 23, enmeshing with the gear 17,

whereby the rotary motion of the axle is transmitted to the counter-shaft. Loosely mounted on the latter are the bevel-gears 24 25, which are provided with clutch-jaws 26 27 on their inner faces, adapted to be engaged by the shifting clutch members 27 28. The latter are connected by the pins or bolts 29, whose heads are chambered within the clutch member 28 and threaded into the member 27, 30 and the coiled springs 30, through which the pins pass, serve to keep the shifting members of the clutch in fixed relation to each other. The distance between the clutch-jaws 26 on the bevel-pinions 24 25 is such with relation 35 to the position of the exterior faces or jaws of the connected clutch members 27 28 that when one of said clutch members is in driving engagement with the bevel-gear the other one is thrown out, and upon a reversal of 40 direction of rotation of the axle the clutch will be shifted thereby into driving engagement with the other pinion. A bevel-gear 31 is enmeshed with both of the bevel-pinions 24 25 and is mounted upon a stub-shaft 32, 45 having a bearing in a forward extension of the gear-casing formed by the members 19 20. Said stub-shaft has a collar 33, which maintains its position by fitting within a bearing formed within the gear-casing, and it being understood that the entire bearing is babbitted or otherwise constructed to maintain the shaft in proper alignment and position. The forward end of the stub-shaft 32 has a friction clutch ring or sleeve 34 keyed thereto, and friction-shoes 35 are applied to said sleeve or ring by the sliding of the clutch-hub 36 and the toggle-links 37 38. The clutch-hub 36 is keyed or splined on the sleeve 39 and the latter in turn is keyed to the shaft 40, which may be the armature-shaft of a dynamo, the position of which is indicated by the dotted lines in Fig. 2. The driven or power-using machine is preferably mounted in a casing the major portion of which may be continuous of or integral with 50 the gear-casing sections 19 20. Preferably, however, the forward ends of said sections are beveled, and a cap 41, which may be of sheet metal, is applied over the dynamo or other machine, suitable provision being made 55 to secure dust-proof joints, and this cap 41 may be held upon the casing by means of the bail 42, having a perforation registering with the perforation in the lug 43, and the two may be secured together—as, for example, by means 60 of the hasp of a padlock. The lug 43 has the inclined or cam surface 44, by means of which the cap 41 can be tightly drawn to its seat to make a dust-proof joint. The forward end of the casing and the driven machine may be suspended from the truck by means of a hanger or stirrup 45, the cross-bar of which is perforated, as shown at 46, for the passage of a pin 47, to which are applied cushion-springs 48 49. It will be understood that some changes in 65 the details of construction may be made while preserving the general features and utilities of my invention. For example, I have shown

a sleeve applied to the axle and prefer to use such a sleeve, because it avoids any necessity of turning or finishing the axle to receive the gear-case, which must be connected to the axle by a practically dust-proof joint and also in such manner that a body of lubricant may be supplied for the gearing if tooth-gears be used. The sleeve also strengthens the axle instead of weakening it. While I have shown and described tooth-gears, friction-gears may be employed and the form of the clutch mechanism may, of course, be varied. I have also shown and described a power-transmitting shaft arranged at right angles to the counter-shaft; but obviously the driven shaft of the power-using machine may be connected directly with the gearing, although in such construction the sudden shocks and jars produced in the starting and stopping of the axle suddenly would be injurious and undesirable.

Among the principal advantages secured in the above-described device are the following: The gearing and the power-using machine are 90 inclosed in a tight or dust-proof casing and the whole is so mounted that it is not affected by the vibrations of the car-body or of the truck itself. The entire apparatus is self-contained—that is, it is mounted within a single 95 support or casing, which is flexibly connected to the truck-frame and is also adapted to vibrate or rock upon the axle. The apparatus, by reason of the use of a parted or sectional casing, can be applied or removed without detaching the axle from the truck and all parts of the apparatus are readily accessible for inspection or repair. It is also obvious that by making the casing sectional, as described, the gearing and the power-driven machine 100 can be removed without disconnecting them, leaving the gear or the gear and sleeve, as the case may be, secured to the axle. The construction of course enables the assembling of all of the parts at the place of manufacture, while the device may be applied to the axle by unskilled labor. 105 110

I claim—

1. A means for transmitting power from car-axles, comprising a gear mounted upon the axle, a counter-shaft arranged parallel to the axle, a gear-casing adapted to be clamped about the car-axle to inclose the gear thereon and the counter-shaft, gearing arranged within said casing and connected to the counter-shaft and clutch mechanism whereby rotary motion of the car-axle in either direction may be transmitted through said gearing in the same direction to a power-using device, substantially as described. 115 120 125

2. In means for transmitting power from car-axles, the combination with a gear mounted upon the axle, a counter-shaft, a gear fixed thereon and enmeshed with the axle - gear, gear-wheels loosely mounted upon the counter-shaft, a power-transmitting shaft geared with said loose gears, and clutch mechanism whereby either of the loose gears may be made fast with the counter-shaft, whereby rotary 130

motion in the same direction may be imparted to the power-transmitting shaft when the axle and counter-shaft are rotated in either direction, substantially as described.

5 3. In means for transmitting power from car-axles, the combination with the axle of a sleeve secured thereon, a gear-wheel secured with the sleeve, a counter-shaft arranged parallel to the axle, gear-wheels loosely mounted 10 thereon and facing each other, a gear fixed to the counter-shaft and enmeshed with the axle-gear, a clutch mechanism adapted to connect either of the loose gears with the fixed gear, and a shaft adapted to be driven in the same 15 direction by either of the loose gears when se-

cured to turn with the counter-shaft, substantially as described.

4. Means for transmitting power from car-axles, comprising, a sleeve adapted to embrace a car-axle and having a gear member 20 thereon, means for fixedly securing the sleeve to the axle and a casing loosely mounted on and surrounding the sleeve, gearing journaled in and carried by the casing meshing with the gear member on the sleeve, and 25 means for securing the casing on the sleeve.
